UNITED STATES PATENT OFFICE.

FREDERICK W. RENWICK, OF CAMDEN, NEW JERSEY.

DIAL FOR RADIO APPARATUS.

Application filed February 16, 1925, Serial No. 9,606. Renewed February 12, 1927.

This invention relates to improvements in dials for radio apparatus.

The primary object of this invention is providing a dial, having a weighted portion, 5 adapted for use in connection with radio apparatus having an unbalanced rotatable element, whereby the weighted portion of the dial will counterbalance the said unbalanced element to prevent unintentional shifting of 10 the said element due to gravitational forces.

A further object of the invention is to provide a dial of the above mentioned type wherein the weighted portion is wholly confined within the margins of the dial.

15 A still further object of the invention is to provide a dial, as set forth above, having the outward appearance, when in use, of an ordinary dial.

Other objects and advantages of the invention will be apparent during the course 20 of the following description.

In the accompanying drawings forming a part of this specification and in which like numerals are employed to designate like 25 parts throughout the same,

Figure 1 is a fragmentary front elevational view of one form of dial embodying this invention;

Figure 2 is a transverse sectional view 30 taken upon line II—II of Fig. 1,

Figure 3 is a rear elevational view, partly broken away, of a modified form of dial embodying this invention,

Figure 4 is a transverse sectional view 35 taken upon line IV—IV of Fig. 3,

Figure 5 is a detail perspective view of the adjustable weight carried by the dial shown in Figs. 1 and 2,

Figure 6 is a rear elevational view of a 40 further modified form of dial embodying this invention,

Figure 7 is a transverse sectional view taken upon line VII—VII of Fig. 6,

Figure 8 is a rear elevational view of a 45 further modified form of a dial embodying this invention,

Figure 9 is a transverse sectional view taken upon lines IX—IX of Fig. 8, and

Figure 10 is a detail perspective view of 50 the type of counterbalancing weight carried by the dial shown in Figs. 8 and 9.

Referring to the accompanying drawings and particularly to Figs. 6 and 7, the numeral 5 designates the body portion of 55 a dial having the hub portion 6 which pro-

jects axially through the hollowed-out part 7 of the said body portion 5, the remaining part of said body portion being solid, as at 8, to provide an eccentrically weighted or overbalanced dial. It is to be understood that this dial may be formed by any suitable operation, such as by molding from bakelite, rubberoid, etc., and the solid or weighted portion 8 is to be formed of the same material from which the body portion 5 is 65 formed.

Referring particularly to Figs. 3 and 4, it will be seen that the body portion 9 of the dial is solid and is provided with a bushing 10. This solid body portion is molded 70 from any suitable material and, during the molding of the same, is provided with a weight or metallic body 11, made of lead or the like, which is entirely embedded within the margins of the dial and is provided with 75 any desired number of apertures 12 through which the material of the body portion 9 may flow for anchoring the weight 11, as shown. It will be understood that this weight 11 produces an overbalanced or eccentrically weighted dial.

By referring particularly to Figs. 1, 2 and 5, it will be seen that a dial is provided with a shell-like or hollow body portion 13 having the integral hub 14 extending axially 85 therethrough which is provided with the bushing 15. Adjustably mounted upon the projecting portion of this bushing 15, the said bushing being formed of greater axial length than the hub 14, is a sector-shaped 90 plate-like weight 16. This weight is mounted upon the projecting portion of the bushing 15 by means of the arms 16^a having the apertured ears 16^b through the apertures of which the screw 16^c extends. It will be noted that this weight 16 produces an overbalanced or eccentrically weighted dial and that the weight may be adjusted in respect to the said dial.

In Figs. 8, 9, and 10, a dial is illustrated 100 as having a shell-like or hollow body portion 17 formed with a hub 18 and a projecting bushing 19. A pair of sector-shaped, plate-like weights 20 are provided and have the apertured ears 20^a adapted for receiving the 105 projecting portion of the bushing 19. For the purpose of retaining these weights 20 in any desired adjusted position, such as illustrated in Fig. 8, a ring 21 is positioned upon the end of the bushing 19 and is held in place 110

by the set screw 22. This ring 21 may be mounted on the projecting portion of the bushing.

5
2. As a new article of manufacture, a radio apparatus dial having a hub portion of less axial length than the axial length of the dial body, a bushing within the bore of the hub portion of greater axial length than the hub portion, and a body eccentrically carried by the projecting portion of the bushing.

10
3. As a new article of manufacture, a radio apparatus dial having a hub portion of less axial length than the axial length of the dial body, a bushing within the bore of the hub portion of greater axial length than the hub portion, and a body eccentrically carried by the projecting portion of the bushing.

15
4. As a new article of manufacture, a radio apparatus dial having a hub portion of less axial length than the axial length of the dial body, a bushing within the bore of the hub portion of greater axial length than the hub portion, and a body eccentrically carried by the projecting portion of the bushing.

20
5. As a new article of manufacture, a radio apparatus dial, and a pair of sector-shaped plates carried by the dial and adjustable in respect to each other and the dial body.

25
6. As a new article of manufacture, a radio apparatus dial, and a pair of eccentric weights carried by and adjustable independently in respect to the dial body.

30
7. As a new article of manufacture, a radio apparatus dial having an overbalancing portion forming a unitary part thereof.

35
8. As a new article of manufacture, a radio apparatus dial, and a metallic body eccentrically carried by the dial and located entirely within its margins.

40
9. As a new article of manufacture, a radio apparatus dial, and a counterbalance weight adjustable in respect to the dial and carried by the same within its margins.

Having thus described the invention, I
45 claim:—

1. As a new article of manufacture, a radio apparatus dial having a projecting bushing portion, and a weighted body

In testimony whereof I affix my signature.

FREDERICK W. RENWICK.
